UNITED STATES PATENT OFFICE.

CHARLES H. WILLIAMS, JR., OF CHICAGO, ILLINOIS, ASSIGNOR TO CHICAGO RAILWAY EQUIPMENT COMPANY, OF CHICAGO, ILLINOIS, A CORPORATION OF ILLINOIS.

REVERSIBLE FULCRUM FOR BRAKE-BEAMS.

SPECIFICATION forming part of Letters Patent No. 722,655, dated March 10, 1903.

Application filed February 12, 1902. Serial No. 93,800. (No model.)

To all whom it may concern:

Be it known that I, CHARLES H. WILLIAMS, Jr., a citizen of the United States, residing at Chicago, in the county of Cook and State 5 of Illinois, have invented certain new and useful Improvements in Reversible Fulcrums for Brake-Beams, of which the following is a specification.

This invention relates to a new and useful 10 improvement in a reversible fulcrum for brake-beams, being designed particularly for use in connection with various types of what are commonly known as "solid" beams.

The objects of my invention are to simplify 15 the construction of devices of the character indicated, so as to enable the same to be easily made, quickly applied, and when in position to rigidly hold the fulcrum in place.

With these objects in view the invention 20 consists in the construction, arrangement, and combination of the several parts, all as will hereinafter be described and afterward pointed out in the claims.

In the drawings, Figure 1 is a top plan view 25 of my improved reversible fulcrum in position on a beam which is I-shaped in section. Fig. 2 is a vertical sectional view through the same on line 2 2 of Fig. 3. Fig. 3 is a sectional view on line 3 3 of Fig. 2. Fig. 4 is a 30 detail view of the clamping-block.

1 indicates the beam, which may be of any usual cross-section, the beam shown in the drawings being I-shaped.

The clamping-block, through the medium 35 of which the fulcrum-block or lever-post is mounted and locked in a rotatably-adjusted position, consists of what I will call "top" and "bottom" cross connecting-pieces 2, whose side edges are reinforced by inwardly-extending flanges 3. The rear edges of these cross connecting-pieces, as well as their forward edges, are provided with seats 4 for receiving the flanges of the I-beam. The rear edges are also bent or flanged inwardly to engage 45 the outer face of the I-beam flange, and these top and bottom connecting-pieces also at their outer edges are connected by straps 5, which straps are preferably integral therewith.

50 The forward edges of the connecting-pieces are reinforced or thickened and are extended

inwardly toward each other outside of the forward flange of the beam, said extensions being provided with semicircular recesses which register with each other when the 55 clamping-block is secured in position to form a circular opening for the reception of the securing-head on the inner end of the lever-post. As shown, this opening is enlarged at its inner edge to receive the head referred to. 60

6 indicates lugs or extensions projecting forwardly from the connecting-pieces, preferably beyond the base of the lever-post.

7 indicates the lever-post, which consists of a base portion 8, having a flanged head 9 65 extending inwardly from its inner face and designed to be received in the opening above referred to.

10 indicates the jaws of the post, which are provided with openings for the reception of 70 the pivot-bolt of the brake-lever, as is well understood.

The base of the lever-post is notched, as at 11, said notches being arranged so as to be circumferentially displaced with respect 75 to the plane of the brake-lever, usually forty degrees; but the degree of displacement may be any desired.

12 indicates a bolt or rivet which is employed for the purpose of securing the clamping-block in position on the brake-beam. As this bolt or rivet passes through the web of the beam and through the connecting-pieces, it will be seen that the clamping-block is absolutely locked against longitudinal displacement. The extensions at the forward ends of the cross connecting-pieces when the clamping-block is secured in place embrace the head of the lever-post, permitting the same to be rotated so as to bring one of the notches 80 11 opposite one of the lugs 6. When the parts are in this position, the lug, which registers with the notch, is bent down into the notch, thus locking the lever-post at the desired angle and in the desired position. If 85 occasion requires a change in the position of the lever-post, the bent lug may be broken, the lever-post rotated to its new position, and the lug which remains on the clamping-block is now bent into its registering notch to lock 90 the lever-post against rotation. While I have shown these lugs as being on the clamping-

block and the notches in the lever-post, it is obvious that the position of these elements may be reversed or that they may be located at other points.

5 I am aware that many minor changes may be made in the construction and arrangements of the parts of my device without in the least departing from the nature and principle of the same.

10 Having thus described my invention, what I claim, and desire to secure by Letters Patent of the United States, is—

15 1. The combination with a brake-beam, of a clamping-block, means for clamping said block on said beam, a lever-post rotatably mounted in said clamping-block, and means in the form of lugs and notches, for locking said lever-post in an adjusted position; substantially as described.

20 2. The combination with a brake-beam, of a clamping-block, means for securing said clamping-block on said beam, a lever-post rotatably mounted in said clamping-block, notches in said lever-post, and a plurality of lugs on said clamping-block for coöperating with said notches to lock the lever-post against rotation; substantially as described.

25 3. The herein-described clamping-block consisting of cross connecting-pieces, straps for connecting one end of said connecting-pieces, and inwardly-extending projections on the free ends of said connecting-pieces; substantially as described.

30 4. The herein-described clamping-block consisting of reinforced cross connecting-pieces, straps for connecting the rear ends of said cross-pieces, inwardly-extending projections on the free ends of said cross connecting-pieces, said projections being formed with registering semicircular recesses; substantially as described.

35 5. The herein-described clamping-block consisting of cross-pieces connected by straps at their rear ends, inwardly-extending projections on their forward or free ends which are designed to embrace and hold the lever-post in position, and lugs extending forwardly from the cross-pieces; substantially as described.

40 6. The herein-described clamping-block consisting of cross connecting-pieces, means for connecting one end of said cross-pieces, and inwardly-extending projections on the opposite ends of said connecting-pieces forming between them a socket for a swiveled member adapted to be held therein; substantially as described.

45 7. The herein-described clamping-block consisting of cross connecting-pieces, integral means for connecting one end of said cross-pieces, and inwardly-extending projections on the opposite ends of said connecting-pieces forming between them a socket for a swiveled member adapted to be held therein; substantially as described.

50 8. The herein-described clamping-block consisting of cross connecting-pieces, in-

wardly-extending flanges on said cross-pieces, means for connecting one end of said cross-pieces, and inwardly-extending projections on the opposite ends of said connecting-pieces; substantially as described.

55 9. The herein-described clamping-block consisting of cross connecting-pieces, inwardly-extending flanges on said cross-pieces, means integral with said cross-pieces for connecting one end of said cross-pieces, and inwardly-extending projections on the opposite ends of said connecting-pieces; substantially as described.

60 10. The combination of a clamping-block, a lever-post clamped thereby and normally revoluble therein, and means integral with one of said parts adapted to lock said post in a predetermined position; substantially as shown.

65 11. The combination of a clamping-block consisting of cross connecting parts, means for connecting said parts at one end of said clamping-block, recessed inwardly-extending projections on the opposite ends of said connecting parts, a lever-post normally revoluble between said recesses, and means integral with one of said parts for locking said post in a predetermined position; substantially as shown.

70 12. The combination of a clamping-block consisting of cross connecting parts, means for connecting said parts at one end of said clamping-block, recessed inwardly-extending projections on the opposite ends of said connecting parts, a lever-post normally revoluble between said recesses, and means integral with one of said parts for locking said post in predetermined positions; substantially as shown.

75 13. The combination of a clamping-block substantially rectangular in cross-section and provided with free ends adapted to form a socket therebetween, of a lever-post held in said socket, and means for locking said post in predetermined positions; substantially as shown.

80 14. The combination of a clamping-block substantially rectangular in cross-section and provided with free ends adapted to form a socket therebetween, of a lever-post held in said socket, and means for locking said post in a predetermined position; substantially as shown.

85 15. The combination of a clamping-block substantially rectangular in cross-section, webs on said clamping-block, said clamping-block being provided with free ends forming a socket therebetween, a lever-post held in said socket, and means for locking said post in a predetermined position; substantially as described.

90 In testimony whereof I hereunto set my hand, in the presence of two witnesses, this 31st day of January, 1902.
